UNITED STATES PATENT OFFICE.

EDWARD THEMAK, OF NEW YORK, N. Y.

LIQUID APPLICATOR.

Application filed September 23, 1925. Serial No. 58,179.

This invention relates to liquid applicators and has for an object to provide an improved construction wherein different kinds of liquid may be readily confined in 5 a container and dispensed and applied to a given spot by the container.

Another object is to provide an improved construction wherein iodine or other liquid is provided in a container having a single 10 small opening whereby it may be readily dispensed in small quantities from the original container.

A still further object in view is to provide a compact liquid applicator for applying iodine or other liquids as desired, the structure including a liquid container having a single opening and a casing for protecting the container against crushing and also for sealing the opening.

20 In the accompanying drawing—

Figure 1 is a view of the complete applicator with the cap slightly removed from the body.

25 Figure 2 is a longitudinal vertical sectional view through an applicator disclosing an embodiment of the invention.

Referring to the accompanying drawing by numerals, 1 indicates a hollow body having a closed lower end 2, a roughened thumb portion 3 and a threaded section 4. Preferably, the body 1 is made from sheet metal and, therefore, preferably the threads 4 are embossed or pressed from the body, though if desired, cut threads could be used. The 30 cap 5 is preferably made from sheet metal and is provided with pressed threads 6, a pressed out roughened thumb portion 7 and a round end 8. When the cap 5 is screwed down tight on the body 1, the cushioning 40 and sealing member 9 in cap 5 having a spherical seat in its lower end presses tightly against the spherical end 10 of the liquid container 11 so as to seal the opening 12. The parts are preferably proportioned so that when the packing or sealing member 9 is pressing tightly against end 10, the lower end 13 of cap 5 is preferably engaging the roughened part 3. Preferably, a cushioning

and packing structure 14 is arranged in the lower end of body 1 so as to relieve the 50 strain on the container 11 which is preferably formed of glass, though it may be formed of other material. The liquid 15 may be iodine or other liquid.

In case the liquid 11 is iodine or other liquid to be applied to sores or cuts, cap 5 may be readily removed by unscrewing and then the spherical end 10 rubbed over the flesh at or near the cut whereupon some of the iodine or other liquid will be fed through 55 the aperture 12 and onto the flesh. As there is only one aperture and that being minute in the container 11, the liquid will not flow through the aperture ordinarily but when the same is rubbed over the flesh, 60 the liquid will automatically move through the aperture and be properly distributed by the spherical end 10 by capillary action. In this way the liquid is dispensed and applied by the original container. Preferably, the 65 container 11 has a sliding fit in the body 1 but may be easily removed at any time so as to place a new container in the body whenever desired.

What I claim is:

A liquid applicator comprising a container having a single minute opening at one end, said end being spherical, a casing covering and protecting said container, said casing being formed with a body and a cap having a spherical end, said body falling short of said container end, said body nearest the container end having a threaded section and a raised roughened bead at one end of the threaded section, said cap having a threaded section and a pad having a concave seat arranged within the spherical end thereof, said pad being adapted to engage the spherical end of said container and close said aperture, the length of the cap and body being such that the cap will be stopped in its movement as it is screwed onto the body by said roughened bead before an undesirable pressure is applied to said container by the pad on the cap.

EDWARD THEMAK.
